UNITED STATES PATENT OFFICE.

CHARLES HENRY DAVIS, OF INVERELL, NEW SOUTH WALES, AUSTRALIA.

TENSION-DISTRIBUTING MEANS FOR MACHINE-SHEAR HAND PIECES.

Application filed October 6, 1924, Serial No. 741,874, and in Australia December 4, 1923.

This invention relates to tension justifying means for shearing machine hand pieces.

When the fork of the vibrating lever of a sheep shearing machine bears directly on the back of the cutter, imperfect distribution of the pressure (called "tension" in the art) results, and the shear then operates unsatisfactorily. The cutter consists of an open bottom sheet metal stamping which is detachably held by the lever fork and works across the comb face; it is taken out of the machine from time to time and ground on the bottom face to sharpen its cutting edges. The grinding is rarely exact and the parallelism of the cutter face with the cutter back is thus frequently rendered so irregular that a tension justifying device must be interposed between the cutter and the fork of the lever. Various devices have been used for this purpose, and though certain of these known devices operate with greater or less utility, all of them which are within my knowledge possess defects which it is desirable to eliminate.

In my invention the forward end of the cutter driving lever is formed as a flat palm with an approximately straight front edge; it is not forked to form claws as is usual in shearing machine construction. The forward part of the lever palm extends slightly forward of the back line of the cutter. A spring tension justifying plate is secured below this palm. This plate extends over the top of the cutter and it bears on the tops of the cutter teeth along its frontal edge, which is finished to the radius of the cutter movement, and it carries the driving dowels and is so shaped that it effects equalized distribution of the tension as between the three teeth of the cutter, so that the necessity for providing a "centre spring finger" or any equivalent device for adjusting the pressure on the "centre finger" in relation to the outer fingers is obviated. The adjustment is perfected in special cases by very slightly grinding down the top face of the centre tooth of the cutter where the tension justifying plate bears upon it. The spring plate is located in a countersunk seating in the bottom side of the lever and it is fixed to the lever by a rivet or screw at its extreme rear end. It is thus rigidly held by the lever but is free to flex to accommodate it to the cutter.

The invention will now be described with reference to the accompanying drawings, in which—

Fig. 1 is a top plan of the fore end of the driving lever finished to a palm, and fitted with a tension justifying plate which is shown bearing on a three tooth cutter of conventional type;

Fig. 2 is a front end elevation of the tension justifying plate, indicating its transverse curvature by reason of which it is caused to contact firstly on the backs of the outer teeth of the cutter, and subsequently on the back of the middle tooth of the cutter. Pressure is therefore applied only on the middle tooth of the cutter when the tension screw is screwed down sufficiently to straighten the plate, the curvature of the plate having regard to its shape, being such that additional pressure applied after an overall equalized bearing is attained results in the application of more pressure on the centre tooth of the cutter than on the outer teeth of the cutter;

Fig. 3 is a longitudinal section on the line 3—3 Fig. 1;

Fig. 4 is a front end elevation of the cutter; and

Fig. 5 is a top plan of the cutter.

The vibrating drive lever 10 may be of any one of the conventional types, but in all cases it is terminated at its forward end in a flat splayed member or palm 11, the forward end 12 of which extends forwardly slightly over the back edge 13 of the cutter 14. The tension justifying plate 15 is a flat plate of spring steel extending across the cutter back 14 and having a rearwardly disposed triangular stub extension 16, the apex at the back end of which is riveted or screwed up at 17 to the wrist portion of the palm 11. The under side of the palm 11 is countersunk to form a neat seating for the stub 16 and the back portions of the lateral parts of the plate so that sidewise wriggling of the plate in the driving lever is inhibited. The forward edge 12 of the palm 11 bears down on the rear part of the justifying plate 15, just forward of the stub part 16 of it. That plate 15 may be scalloped, fluted, or otherwise thinned as shown at 18 on the top side of it near its front edge in order to augment its flexibility laterally without materially diminishing its longitudinal stiffness;

it is also curved transversely so that when free it is slightly concave on the under side, and it should be hollow ground or relieved behind its forward bearing edge as shown at 5 19 so that it contacts with the backs of the cutter teeth only on a line as nearly as possible forward on the cutter teeth backs. This is clearly seen in Fig. 3. The driving dowels 20 are fixed in the justifying plate 10 15, and as usual they take into the drive holes 21 in the cutter back. Facility of adjustment is obtained in particular cases by more or less grinding down the top face of the middle tooth of the cutter as shown at 22. 15 This grinding down is effected by the shearer, and is resorted to only for the purpose of modifying the adjustment as between the outer teeth and the middle tooth which is otherwise obtained by means of the plate 15. 20 When tension (downward pressure) is applied to the drive lever 10, it is transmitted through the justifying plate 15 to the cutter 14. Consequent on the lateral curving of the justifying plate 15, this plate contacts 25 first with the backs of the outer teeth of the cutter, as tension is increased it flexes transversely so that the middle portion of it then contacts with the back of the middle tooth of the cutter. Further increase in the tension 30 after the point of equalization is passed results in disproportionate increase of pressure on the middle tooth as contrasted with the pressure applied to the two outer teeth of the cutter. By using the ordinary tension 35 adjustment screw the shearer is enabled to ease up or intensify the tension on the middle point of the cutter, whilst maintaining tension on the outer teeth of it.

In view of the flat wing like form of the 40 plate 15, it is capable of flexing more or less freely upwardly when considerable pressure is applied to the cutter lever 10, but its freedom to flex upwardly is greater at the sides than at the centre, so that when a heavy 45 tension is applied to obtain a desirable cutting contact at the middle tooth, the tension is not augmented to the same extent on the

outer teeth as on the centre tooth, this by reason of its elasticity at its outer portion.

The flat shape of the justifying plate and 50 its close down location over the cutter back minimizes the risk of its catching in the fleece during the shearing of sheep as it works freely in the opening in the fleece and does not operate to open out the cut fleece 55 laterally.

What I claim as my invention and desire to secure by Letters Patent is:—

1. A sheep shearing machine including a cutter lever with its fore end shaped as a 60 broad flat palm with approximately straight front edge and a flexible tension-justifying plate with its front edge finished to the radius of the cutter movement and bearing downward on the backs of the cutter teeth 65 near their forward ends, said plate having a rearward central angular stub located in a countersunk seat and fixed near its rear end to the underside of said lever.

2. A sheep shearing machine tension adjusting device intermediate the cutter lever and the cutter, constituted of a flexible flat plate carried by the cutter lever and having its front edge finished to the radius of the cutter movement and adapted to closely overlie 75 the cutter back and to bear at its front edge only at forward positions on the backs of the cutter teeth.

3. A sheep shearing machine tension adjusting device according to claim 2, having 80 the flexible flat plate scalloped or fluted longitudinally on the top face of it adjacent its bearing edge.

4. A sheep shearing machine tension adjusting device, according to claim 2 normally 85 curved to bear initially on the outer teeth of the cutter and by virtue of its flexibility and plain shape adapted to flex more freely at its ends than at its mid part when tension is applied to the lever.

In testimony whereof I have signed my name to this specification.

CHARLES HENRY DAVIS.
